UNITED STATES PATENT OFFICE.

ALBERT TROLLOPE, OF DETROIT, MICHIGAN.

STOVE-PIPE FASTENER.

SPECIFICATION forming part of Letters Patent No. 236,921, dated January 25, 1881.

Application filed May 8, 1880. (Model.)

To all whom it may concern:

Be it known that I, ALBERT TROLLOPE, of Detroit, in the county of Wayne and State of Michigan, have invented a new and useful Improvement in Stove-Pipe Fasteners, of which the following is a specification.

My invention has for its object the secure and close fastening of stove-pipes to their wall-holes, thereby securing a certain and safe connection and avoiding all danger from their falling, and, by closing all unnecessary opening, improving the draft.

The invention consists of a circular metallic wall-plate with a circular opening in its center large enough to admit the pipe. Around half of this opening is a flange, cast on the plate, about one inch in depth. To this flange is attached, by bolts and nuts, an adjustable metallic band of the same shape and size as the flange, and in alike position as to the other half of the opening. It is by means of this band, when fastened in its place, that the pipe is firmly secured to the plate and chimney hole. Two iron straps fastened opposite to each other on the inside rim of the plate extend inwardly, so that when the plate is against the wall their ends reach into the flue of the chimney. On the ends of those straps are adjustable pieces of L shape, secured by bolts, in the cross-limb of which are thumb-screws, which, when adjusted, press against the side of the flue, and thus draw the plate closely and securely to the wall. An outside metallic covering, whose cross-section may be of ogee or any suitable shape, is fastened by lugs which enter and are pressed into wedge-shaped recesses in the plate, and is designed to give a suitable finish to the improvement.

In the drawings, similar letters indicate like parts.

Figure 1 is a perspective view of the device with the outside covering off. Fig. 2 is a horizontal cross-section, showing the device attached to the chimney.

In the drawings, A A represent the wall-plate; B, the flange around half the opening; C, the adjustable flange, which is secured to the flange B by the bolts a a', which pass through suitable pieces or flanges, b b' c c', at the ends of the flange B and band C. This flange and band, together with their fastening

devices, constitute a clamp by which the stove-pipe is firmly held in position. From the outside center of the band C projects a piece or lug, b, which plays loosely inside a couple of small prongs or hooks which rise from the plate, the object being to keep the band in its place near the plate. D D are metallic straps fastened to the plate A A by the nuts e e', to the ends of which straps are attached the adjustable L-shaped pieces E E, by bolts through the slots f f', near the ends of the straps, and by reason of which they may be lengthened or shortened to suit the varying thickness of chimneys. Through the end of the adjustable angular extensions E E are set-screws h h', pointing inwardly toward the plate, and which, screwed in place, press against the side of the chimney-flue F F, and thereby draw the wall-plate A A close and securely against the wall.

G represents a rose-plate, which is attached to the wall-plate by means of the lugs i i, which project inwardly from the rim, and which are made to enter and fasten into the wedge-shaped recesses K K', which are formed for that purpose on the wall-plate. The projections m m' are simply intended for rests for the rose-plate when in place.

The method of fastening the device to the wall and to the pipe is simple, and it is easily done. The bolt which fastens one of the straps to the plate is first loosened, so that it may have play enough to enter the chimney-hole. When the plate is against the wall, see whether the adjustable angular extensions E E are of the right length; if not, adjust them, put device back in place, and tighten the bolt which secures the strap. The adjuster's arm may then be placed in through the pipe-hole, and the set or thumb screws screwed up until they press firmly against the wall. The pipe is then put in place, the rose-plate G being first slipped over it, and the adjustable band bolted firmly down in place around the pipe, which is thus securely and rightly fastened. The rose-plate is then slipped to its place and turned till securely fastened.

What I claim as my invention is—

1. In a stove-pipe fastener, the combination, with a wall-plate having a pipe-opening, one portion of which is provided with an outwardly-projecting flange, of an independent band

which extends about the remaining portion of the opening, and screw-bolts which connect both extremities of said flange, respectively, with the corresponding extremities of said band, substantially as set forth.

2. In a stove-pipe fastener, the combination, with a wall-plate having one portion of its pipe-opening provided with an outwardly-projecting flange, of a band which extends about 10 the unflanged portion of the opening, and screw-bolts which connect together corresponding ends of the flange and band, said band being provided with a lug which engages with two prongs projecting from the wall-plate, substantially as set forth.

3. In a stove-pipe fastener, the combination, with a plate adapted to fit against the wall, and a clamp extending in outward projection about the pipe-opening, of a rose-plate which 20 covers said clamp and wall-plate, and fastening devices which detachably secure the rose-plate to the wall-plate, substantially as set forth.

4. In a stove-pipe fastener, the combination, 25 with a plate adapted to fit against the wall, and a clamp which extends in outward projection about the pipe-opening, of a rose-plate which covers the clamp and wall-plate, said rose-

plate having its rim provided with inwardly-projecting lugs, which pass through recesses 30 formed in the wall-plate and engage with the rear side of the latter, substantially as set forth.

5. In a stove-pipe fastener, the combination, with a wall-plate provided with metallic straps adapted to fit within the flue, of angular extensions secured to the inner extremities of 35 said straps, and screws supported by said extensions and adapted to have end bearing against the inner side of the chimney-wall, substantially as set forth.

6. In a stove-pipe fastener, the combination, with a wall-plate provided with metallic straps which extend within the flue, of angular extensions secured in longitudinal adjustment to the inner extremities of the straps, and screws 45 supported in said angular extensions and adapted to have end bearing against the inner side of the chimney-wall, substantially as set forth.

In testimony whereof I sign this specification 50 in the presence of two witnesses.

ALBERT TROLLOPE.
